MAGAZINE HEATER

Ernest L. Cox and John W. Guice, Metropolis, Ill.,
assignors to Wilson Stove and Manufacturing
Company, Inc., Metropolis, Ill., a corporation
of Illinois

Application October 15, 1947, Serial No. 779,942

1 Claim. (Cl. 126—73)

1
This invention relates to improvements in magazine heaters for burning coal and other solid fuels.

While the present invention may be embodied in various useful forms, the form disclosed herein is especially suitable for space heating by radiation directly from the heater itself.

However, the invention may be employed with circulation systems. The heater of our invention is further especially adapted for retaining a large amount of fuel so that on one filling it may burn for two or more days. In the preferred form this is obtained by feeding the fuel into the top of the fire pot and providing a heater construction which is well adapted for efficient combustion of the fuel progressively from the bottom of the stored quantity to the top thereof.

A fire pot having a size ample for containing several days supply of solid fuel is provided with a large number of perforations in its vertically extending annular wall through which the incompletely burned gases and smoke escape outwardly into an annular space surrounding the fire pot, where they encounter a fresh supply of air to support and complete their combustion. The products of the combustion in the annular space are then returned, in large part through other perforations near the top of the fire pot and pass from there into the smoke box through which they are then discharged into a chimney.

One of the objects of the invention is to provide a heater having a large fire pot in which can be stored a large amount of solid fuel, such as coal, and having a secondary combustion space outside of the fire pot in which partially burned fuel gases are mixed with fresh air and there consumed.

Another object of the invention is to provide a heater having the foregoing features and having the secondary combustion space located annularly about the fire pot and confined by a wall heated by the secondary combustion for the purpose of radiating heat into the circumambient atmosphere.

Another object of the invention is to provide a heater of the type described including a fire pot having a top feed opening and surrounded by an annular secondary combustion space for receiving fuel gases from the fire pot and with means for forcing the products of combustion developing in the annular space back again into the top of the fire pot before exiting to the smoke pipe.

Other objects and advantages of the invention will be mentioned specifically hereinafter or will

2
become apparent from a perusal of the following specification.

On the drawings:

Figure 1 is a perspective view of a heater made in accordance with my invention, with portions thereof broken away to show the internal construction;

Figure 2 is a vertical central sectional view through the heater;

Figure 3 is a horizontal sectional view on the line III—III of Figure 2;

Figure 4 is a horizontal sectional view on the line IV—IV of Figure 2;

Figure 5 is a perspective view of one of the fire pot sections; and

Figure 6 is a perspective view of showing the manner of assembling the fire pot from a plurality of fire pot sections.

Referring further to the drawings, the heater comprises a base 10 having a plurality of ventilating apertures 11 for permitting natural circulation of air through the base. Upon the base is mounted an imperforate plate 12 upon which rests the ash pit chamber 13 which is provided with a hinged door 14 for facilitating the withdrawal of ashes accumulated in the ash receptacle 15.

The top edge of the ash pit chamber is provided with an inwardly extending flange 16 having an aperture 17 of substantial area for permitting upward flow of air from the ash pit into the secondary combustion space generally indicated as 18.

Supported on the flange 16 which has a circular inner margin is a grate supporting ring 19 which in turn on its lower flange 20 supports a stationary grate member 21 having a plurality of ports 22 for the admission of air from the ash pit into the fire pot. This stationary grate member is provided with pairs of vertically spaced apart flanges 23 and 24 which furnish support for a horizontally oscillatable grate 25 having projections such as 26 and 27 extending between the flanges. The oscillatable grate may be oscillated by means of a handle 28 which is an extension of the projection 27. A cone or deflector 29 is supported as shown on the grate 25 to elevate the bottom of the fuel bed slightly above the center of the movable grate. A plurality of ports 30 provided in the movable grate admit air from the ash pit into the bottom of the fire pot.

Supported also on the ring 12 is a tubular jacket 31, which in the operation of the device is the principal heat radiating surface and which is also apertured at the front of the heater to

provide an opening closable by the ash pit door 14.

The fire pot for convenience is preferably made from a plurality of cast iron sections 32 of more or less identical design, one of which is shown in perspective in Fig. 5. Each fire pot section is provided with a plurality of apertures 33 and with downwardly depending lugs 34 for interlocking cooperation with supporting structure therebelow, and with notches 35 for interlocking cooperation with fire pot sections, if any are mounted thereabove. Each section also has a flange 36 and a flange 37 which in the assembly shown in Fig. 6 overlap contiguous fire pot sections and are bolted thereto, through bolt holes such as 38 and 39.

The number of fire pot sections required to comprise one fire pot ring is of course optional, dependent upon the size of the fire pot to be built and upon other considerations. Likewise the number of superposed fire pot ring sections to be employed is also subject to variation. As indicated in Fig. 6, lugs 34 will rest in the notches 35 and thus adequately unite the two superposed rings. Likewise the lugs on the lowest ring section will enter into suitable notches provided in the ring member 19 resting upon the top of the ash pit chamber.

A top of the fire pot is partially closed by a baffle plate 40 having near its forward edge a large aperture 41 through which fuel may be introduced into the top of the fire pot. Additional small restricted apertures 42 and 43 are also located as shown near the front corners of this baffle plate to eliminate kick back and puffing. These restricted apertures register with top of the annular space defined by the fire pot and the jacket 31.

The marginal edges of the baffle 40 rest upon an inwardly extending continuous flange 44 on the jacket 31, and the edges of the baffle support the peripheral flange portion 45 of the smoke box 46 which has a flanged port 47 for the attachment of the usual smoke pipe. The smoke box is provided at its forward side with a large opening 48 which is normally closed by the door or lid 49, which may be lifted when fuel is being fed into the fire pot.

In the ash pit door 14, I provide a draft regulator 50 of ordinary construction having ports regulated by sliding movement of a gate so that it may regulatably control the admission of air into the ash pit. The hinged door 50 is provided so that the movable grate may be actuated by a tool inserted through the door 50. Any other suitable form of draft regulator and tool opening may be employed.

In the operation of the device the lid 49 will be raised by means of the handle 51 and coal or other solid fuel introduced through the fuel opening 41 into the fire pot until the fire pot is full. Assuming that the fuel first introduced has been ignited before the remainder is introduced, or that there was a layer of fuel already burning on the grates, the combustion will proceed as follows: Air from the ash pit enters through the apertures 30 and 22 into the bottom of the fire pot for initial or partial combustion of the fuel. The total amount of air admitted in this manner is less than that required for complete combustion. The partially burnt fuel gases pass radially outwardly from the fire pot through the various ports 33 into the secondary combustion space 18 where they encounter a fresh supply of air admitted from the ash pit through the front port

17 in the plate 16. Here these fuel gases are completely burned and the heat thereby produced is absorbed in large part by the heat radiating jacket 31. In view of the fact that the baffle 40 is located as shown and has only two small restricted apertures 42 and 43 through which these burning gases could escape directly to the smoke pipe the bulk of the products of combustion or burning gases will be deflected by the baffle into the fire pot through the ports 33 in the upper part thereof. These gases may also enter the top of the fire pot through various notches 35, a number of which are arranged about the upper edge of the top fire pot ring section. These gases reentering the fire pot will then be able to exit through the large port 41 into the smoke box 46 and then flow to the smoke pipe. While these products of combustion are passing through the smoke box, they of course heat the box and it becomes a radiator of a large amount of heat.

For purposes of observation we may optionally provide an aperture in the jacket 31 and cover the aperture with a plate 52 having a plurality of ports therein each of which would be covered by isinglass 53, or some other suitable transparent or translucent material.

When good draft conditions exist in this heater the movable grate may be actuated by a tool extended through the draft regulator opening and applied to the handle 28, and while ashes are falling into the ash pit the existing draft will suck the dust up through the enlarged opening 17 and deliver it to the smoke pipe. Thus the dust will not puff out through the draft regulator opening.

When the heater is in operation there will be some tendency for the draft to pull air and combustion gases directly through the fire pot and fuel inlet port 41 to the smokestack. However the charge of fuel directly on top of the zone of fire in the fire pot will impede such flow of gases to a marked extent. Accordingly, these gases may flow with less restriction by emerging through the ports 33 radially into the secondary combustion space 18, aided by the draft therein, and then back again into the upper end of the fire pot and out through port 41 into the smoke box. While partially burned products of combustion flow into the secondary combustion space 18, they of course encounter an ample supply of fresh air and will then become completely burned. The heat produced by that secondary combustion is to a large extent radiated to the surrounding atmosphere through the jacket 31.

As indicated, the ports 33 are numerous and quite uniformly spaced on the fire pot wall to induce uniform egress of fuel gases from the active fire zone in the fire pot at whatever levels it may exist. The holes should be small enough, however, to prevent loss of solid fuel.

It will, of course, be understood that various structural details of the invention may be varied through a wide range and that the invention may be embodied in various forms differing considerably from each other and from the embodiment herein shown, without departing from the principles of the invention, and it is, therefore, not the purpose to limit the patent granted hereon otherwise than necessitated by the scope of the appended claim.

We claim as our invention:

A magazine heater comprising a base having a front side and a top wall, an upright ash pit defining member on said top wall having an open

front cylindrical portion inwardly from and substantially concentric with the periphery of the base and laterally extending portions at the sides of the open front of the cylindrical portion terminating at the front side of the base, a grate ring supported by the cylindrical portion of said member, a tubular fire pot supported by said grate ring, said tubular fire pot including a plurality of segmental cylindrical perforated plates with offset flanges on diagonally opposite ends thereof for cooperating with flanges of the adjacent plate to form a continuous ring, said ring having lugs and lug recesses on opposed edges thereof for mating with an adjacent ring of plates, a jacket on said base surrounding said ash pit defining member and said tubular fire pot and having an opening in the front thereof aligned with the space between said laterally projecting portions of said ash pit defining member, a door for closing said opening, said ash pit defining member and fire pot being in spaced relation from said jacket except at said opening, the space enclosed by said ash pit defining member between said laterally extending portions being in communication with the space between the jacket and tubular fire pot, a baffle on top of said jacket, a smoke hood on top of said baffle

10

15

20

25

having a smoke outlet, apertures in said baffle connecting the space in the smoke hood with the space between the jacket and fire pot and with the fire pot for creating an updraft, and said updraft being effective to pull dust out of the ash pit chamber through said space between the laterally extending portions even when said door is opened, whereby ash dust will not be discharged through said opening in the jacket.
